UNITED STATES PATENT OFFICE

CLIFFORD ROBERTS, OF REIGATE, ENGLAND, ASSIGNOR TO UNITED SHOE MACHINERY CORPORATION, OF PATERSON, NEW JERSEY, A CORPORATION OF NEW JERSEY

HEEL FOR BOOTS AND SHOES

Application filed May 1, 1925. Serial No. 27,125.

The present invention relates to resilient tread members for boots and shoes and more particularly to heel members designed for attachment to a boot or shoe either as a whole heel, half heel or tread lift.

The conventional type of resilient heel member employs a series of nail retaining devices in the form of washers embedded in a predetermined arrangement within the body 10 of the heel. Due to certain practical disadvantages incident to the employment of these washers, it has been suggested that heels of this type be provided with a nail retaining core embedded in the body of the heel adjacent 15 the attaching face and serving as a medium through which the heels may be attached to a boot or shoe. The use of such a nail retaining core permits the attaching nails to be inserted in any desired arrangement 20 within the area circumscribed by the core and provides a substantially unyielding heel base in contact with the supporting surface of the boot or shoe. This type of heel, however, requires a core which is capable of penetration 25 by the attaching nails, which will not permit withdrawal of the attaching nails therethrough as the result of strains imposed upon it during the wear of the heel, and which may be bonded to the heel body in such 30 a manner that the resilient body portion of the heel will not be separated therefrom during use. This necessarily involves careful selection of the nail retaining core with attendant increased expense.

It is the object of the present invention to improve resilient tread members in a manner to retain certain of the advantages of an unyielding core while at the same time permitting the employment of relatively cheaper 40 materials for this purpose.

In addition it is a further object of the invention to provide an improved form of resilient tread member having an unyielding core adjacent the attaching face combined with nail retaining devices which insure 45 against withdrawal or loosening of the holding nails after the attachment of the heel member to a boot or shoe.

According to the present invention, the heel 50 member is provided with a resilient body

portion having an unyielding core embedded therein adjacent the attaching face. Co-operating with the core are a plurality of eyelets or washers which serve as nail holding devices and relieve the core of the strains 55 ordinarily imposed thereon through the attaching nails. By employing the core merely as a filler and base member, relatively cheap material may be employed such as fiber, leather-board, or a single sheet of wood, certain of these materials being poorly bondable or not bondable with the resilient body 60 of the heel. The nail retaining eyelets may be inserted in pre-arranged location in the core prior to its introduction in the heel mold, 65 thus permitting the core to be used as a washer carrier and simplifying the handling and location of these devices. In the actual production of the heel, the eyelets or washers may remain partially embedded in the core 70 or may be withdrawn therefrom during the formation of the heel body and remain embedded in the heel body independently of the core which is located in proximity to the attaching face of the heel. The finished heel is 75 in all respects the equal of the usual resilient heel having embedded washers or similar nail retaining devices with the additional advantage due to an embedded unyielding core located at the attaching face and forming a 80 rigid base for supporting the heel after its attachment to a boot or shoe.

In the accompanying drawings illustrating the preferred form of the invention, Fig. 1 is a plan view of the attaching face of a heel 85 embodying the features of the invention; Fig. 2 is a section in elevation of the heel shown in Fig. 1 enclosed in a suitable forming mold; Fig. 3 is a plan view of a core having a series of eyelets embedded therein in predetermined arrangement; Fig. 4 is a cross section of the core shown in Fig. 3; Fig. 5 is a plan view of a woman's top lift embodying the features of the invention in a slightly modified form; Fig. 6 is a cross section of the heel 95 shown in Fig. 5; Figs. 7 and 8 are a plan view and cross section respectively of a core provided with embedded eyelets; Fig. 9 is a view partially in section illustrating the parts of a heel partially enclosed in a forming 100

mold prior to the closing of the mold; Fig. 10 is a section illustrating the mold and heel parts shown in Fig. 9 and showing the manner in which the core is forced to the bottom of the mold and the eyelets are separated from the core and caused to remain embedded midway of the depth of the heel; Fig. 11 is a plan view of the heel formed as illustrated in Fig. 10; and Fig. 12 is a cross section of the heel shown in Fig. 11.

As illustrated more particularly in Figs. 1 to 4 inclusive, the present form of heel comprises a core member 20, which is preferably constructed of a cheap material, such as fiber, leather-board, or wood having the desirable supporting qualities. This core has a generally heel shaped outline and is chamfered about the margin at 22 to promote the bond between the core and body of the heel. Prior to the introduction of the core into the heel mold, a series of eyelets 24 of conventional form are inserted in the body of the core with the upper funnel shaped heads projecting from the core. These eyelets may be quickly and easily inserted in a predetermined arrangement by machine. After the formation and loading of the core with eyelets or washers, the core is assembled in a heel mold having a bottom plate 26, a top plate 28, and an intermediate portion 30. The bottom plate of the heel mold is shaped to form the attaching face of the heel and may be provided with locating pins 32 which register with recesses 34 formed in the core to hold the latter in position during the vulcanizing operation. A rubber blank 40 of suitable size and shape is superimposed over the core and after application to the top plate the assembly is subjected to heat and pressure in the usual manner. This causes the rubber compound to flow about the core and nail retaining eyelets, as indicated in Fig. 2, the finished heel having a resilient body portion with an unyielding core embedded therein at the attaching face and a series of nail holding washers embedded in the body portion according to a predetermined location. The location of the nail retaining devices within the body of the heel may be indicated, if so desired, by a series of guide projections 42 formed on the top plate of the mold and serving to form guide openings or depressions in the tread face of the finished heel, these openings registering with the nail retaining washers embedded within the heel. As indicated more particularly in Figs. 1 and 2, the attaching face of the heel is provided with a fin or marginal portion 44, which extends inwardly over the core from the outer edge and serves to enhance the bond between the core and resilient body of the heel. It will be evident to those skilled in the art that as no strain is imposed upon the core tending to withdraw it from the surrounding body portion a relatively slight bond be-

tween the core and body of the heel is ordinarily sufficient. It will be evident furthermore that with this construction the nail retaining washers or eyelets are locked in the resilient body of the heel independently of the core, due to the flow of the rubber compound between the flaring heads of the eyelets and the adjacent face of the core.

In the form of heel shown in Figs. 5 and 6, the core 20 is embedded at the attaching face of the usual body portion 40 and is provided with a single embedded eyelet 24 for the reception of an attaching nail. The attachment of this type of heel is ordinarily accomplished through the employment of a single attaching nail or screw supplemented by the use of blind nails to prevent turning of the heel with respect to the shoe heel.

If so desired, the form of heel may be slightly varied from that shown in Figs. 1 to 4 inclusive without departing from the essential features of the invention. In the form of heel shown in Figs. 7 to 12 inclusive, the nail retaining eyelets 24 may be embedded flush with the core 20, as indicated clearly in Fig. 8. The core is located on shouldered mold pins 60 mounted in the bottom plate 62 and initially holding the core above the bottom of the mold through the engagement of the embedded eyelets with the shoulders 64 formed upon the mold pins. After the rubber blank 66 has been superimposed over the core and the top plate 70 of the mold applied, the core is forced downwardly over the shoulders of the mold pins into the position shown in Fig. 10. In this position, the eyelets are disengaged from the core and remain embedded in the heel body midway between the top and bottom. The openings formed in the core through the embedding of the eyelets therein are of sufficient size to permit the core to be forced down to the bottom of the mold cavity without injury. With this form of heel, as shown more particularly in Fig. 10, a rigid unyielding core or base member 20 is located at the attaching face of the heel and in addition the nail retaining washers or eyelets 24 are embedded within the heel independently of the core, the location of these washers being indicated by guide openings or depressions 42, as shown in Fig. 2. This method of forming the heel has the advantage that the location of the washers with respect to the depth of the heel may be controlled independently of the thickness of the core, the location of these washers being obviously governed by the projection of the mold pins. This construction has the further advantage that the locking of the washers within the resilient heel body is effected independently of the initial insertion of the washers within the core or carrier.

It will be evident that, according to either of the methods disclosed, the nail retaining washers may be easily embedded within the

core, providing only that the core is composed of a material penetrable by the washers or eyelets and serving to hold the washers or eyelets temporarily in position during the handling of the core and the formation of the heel.

5 I claim:

1. A heel member comprising a body portion of resilient material, an unyielding core embedded in the body portion adjacent the attaching face, and a series of metallic nail retaining devices embedded within the body portion of the heel below the attaching face.
- 10 2. A heel member comprising a resilient body portion, a heel shaped core of unyielding material embedded in the body portion adjacent the attaching face, and a series of nail retaining devices embedded in the body portion beneath the core.
- 15 3. A heel member comprising a body portion of resilient material, a heel shaped core of unyielding material embedded in the body portion adjacent the attaching face, and a series of nail retaining devices having tubular shank portions and flaring head portions embedded in the resilient body portion below the attaching face.
- 20 4. A heel member comprising a body portion of resilient material, a heel shaped core of unyielding material embedded in the body portion adjacent the attaching face and having a chamfered margin, a marginal flange extending inwardly from the body portion over the chamfered margin of the core at the attaching face, and a series of nail retaining devices embedded in the resilient body portion below the attaching face.
- 25 5. A heel member comprising a generally heel shaped core of unyielding material, and a metallic nail retaining device having a tubular shank portion and a flaring head portion partially embedded in the core.
- 30 6. A heel member comprising a generally heel shaped core of unyielding material, and a series of metallic nail retaining devices partially embedded in the core.
- 35 7. A heel member comprising a body portion of resilient material, a core of unyielding material embedded in the body portion adjacent the attaching face and bonded thereto during the vulcanizing operation, and a series of eyelets embedded in the core.

40 In testimony whereof I have signed my name to this specification.

CLIFFORD ROBERTS.
